UNITED STATES PATENT OFFICE.

LOUIS MOSKOWITZ, OF BROOKLYN, NEW YORK, AND BENJAMIN J. COHON, OF WESTWOOD, NEW JERSEY.

STRIKER PLATE FOR LOCKS.

Application filed August 6, 1920. Serial No. 401,571.

To all whom it may concern:

Be it known that we, LOUIS MOSKOWITZ and BENJAMIN J. COHON, citizens of the United States, and residing in Brooklyn, in the county of Kings and State of New York, and Westwood, in the county of Bergen and State of New Jersey, respectively, have invented certain new and useful Improvements in Striker Plates for Locks, of which the following is a specification.

Our invention relates to an improvement in striker plates; particularly a striker plate for a locking device to be engaged by a latch or bolt; and one of the objects of said invention is to provide a striker plate that is of simple construction, of few parts, and capable of being easily, quickly and cheaply made, by stamping, casting or otherwise working the material out of which the same is produced. Other objects and advantages of this invention will more fully appear from the following description, which is to be taken with the accompanying drawings showing the best form of our invention now known to us; and the novel features of our improved striker plate are precisely defined in the appended claim. This disclosure however is of course illustrative only and we may use forms of our invention different from those actually shown herein, but embraced within the general meanings of the terms in which the claim is expressed.

On the drawings:—

The figure is a perspective view of a striker plate according to our invention.

The same characters of reference indicate the same parts throughout.

The striker plate comprises a body 1 which is in the form of a flat plate, and provided at the adjacent end with an opening 2. This opening receives the bolt or latch of the locking device when the bolt or latch is shot to locking position. As will be understood the striker plate will usually be mounted upon the frame of the door and the locking device upon the door itself. To this end the striker plate will be fastened to the inside of the door frame in such position that the end having the opening 2 will project slightly beyond the face of the frame; and the lock will be secured to the face of the body of the door in such position that when the door is closed the bolt or latch of the locking device will be in line with the open-

ing 2 and can readily enter and engage the same when the door is made fast. Of course the manner in which the locking device and striker plate are to be mounted is not material as they can be secured in various positions to give the desired result.

From one face of the striker plate adjacent the opening 2 and towards the end remote from the end near which this opening is put extends a projection 3, at the proper angle to the face of the plate 1 and having a hole 4 for a screw or other fastening member. The top and bottom of the projection 3 is connected to the top and bottom edges of the plate 1 above and below the opening 2 by triangular webs 5. The portion 6 of the plate 1 on the opposite side of the projection 3 is provided with several holes 7 for the same purpose as the hole 4.

To mount this striker plate in operative position it is applied to the corner or edge of a door frame so that the portion 6 engages the side of the frame and projection 3 the face of the frame; screws or fastening members being inserted into the holes 4 and 7 and fixed to the frame to hold the striker plate tight. The webs 5 will then be in horizontal position and the opening 2 will be in line with the latch or bolt of the locking device when the door in the frame is shut, so that when the latch or bolt is projected to fasten the door it can pass through the opening 2 parallel to the projection 3. This projection will of course extend away from the edge of the door so that the flat side of the plate 1 will be presented to the edge of the door when the edge of the door moves adjacent the striker plate as the door swings to open or to shut.

This design of striker plate is made in one piece and can be produced either by stamping or machining.

The striker plate above described can be made as strong as needed and at low cost, and can readily be mounted upon doors, windows, etc., to cooperate with almost any form of bolt or latch that one may desire to use.

If desired the striker plate may be housed in by providing a cover plate to be attached to the outer edges of the webs 2, the projection 3 and the adjacent edge of the plate 1.

Having described our invention, what we believe to be new and desire to secure and

protect by Letters Patent of the United States, is:—

A striker plate comprising a body having a projection extending substantially at right angles thereto from one face thereof adjacent one end of same to engage the face of a supporting frame, said body having an opening therethrough between said end and said projection, and webs uniting both ends 10 of the projection to the body above and be-

low said opening, said projection and the portion of the body on the side of the web opposite the opening having holes to give passage to fastening members.

In testimony whereof, we have signed our 15 names to this specification this 22nd day of July, 1920.

LOUIS MOSKOWITZ.
BENJAMIN J. COHON.
